UNITED STATES PATENT OFFICE

CHARLES H. FRANZ, JR., OF MILWAUKEE, WISCONSIN

LOOSE-LEAF BINDER

Application filed August 25, 1928. Serial No. 302,034.

This invention relates to a loose leaf binder.

In loose leaf binders, as heretofore constructed, two general types have been employed. One of these types uses a locking slide for locking the binder closed, and another type uses adjustable screws for locking the binders together, and holding the sheets.

This invention is designed to provide a loose leaf binder, which has the advantages of both a quickly operable locking slide, and also that of the adjustable screws, so that the device may be quickly locked or unlocked, and also so that the screws may be adjusted to exert any desired degree of pressure upon the 15 closed sheets.

This invention is an improvement over that disclosed in my co-pending application for loose leaf binder, Serial No. 35,084, filed June 5, 1925.

Further objects of this invention are to provide a loose leaf binder, in which the screws are provided with heads accessible outside of the binder after the locking slide has been operated to lock the binder parts together, so that the screws may be adjusted, after the locking has taken place, from the outside of the binder, and a further object is to so construct the screws that they provide shoulders immediately below the constricted necks so that the top of the binder cannot drop down out of place during positioning and so that the slide is, in all adjustments held in correct alignment with the constricted necks of the screws.

An embodiment of the invention is shown in the accompanying drawings, in which:

Figure 1 is a fragmentary vertical, sectional view through a portion of the binder, such view corresponding to a section on line 1—1 of Figure 2.

Figure 2 is a sectional view on the line 2—2 of Figure 1.

Figure 3 is an enlarged sectional view on line 3—3 of Figure 2.

Referring to the drawings, it will be seen that the binder is provided with a pair of covers which are flexibly joined to the back of the binder. For convenience, one of the covers, as indicated by the reference character 1, will be termed the bottom cover, and the

other, indicated by reference character 2, the top cover. These covers are joined to slidably associated back portions 3 and 4, arranged at right-angles to the closure planes of the covers. These back portions are reinforced by means of the L-shaped metal reinforcing plates 5 and 6. Suitable filling members are employed in the covers, as indicated at 7. In addition to this, each cover is provided with a flexible reinforcing strip 8, and the faces are finished by the cover strips or outer sheets 9. The filling strips 7 stop short at a slight space from the back of the binder to provide the requisite flexibility at this point in the well known manner.

The bottom of the binder is provided with a plurality of tubular posts 10 which are riveted to the metal reinforcing plate 5, as shown in Figure 1, and if desired a filling strip 11 may be positioned below the bottom of the posts. These tubular posts 10 extend upwardly and are preferably constricted at their upper ends and threaded to receive the adjustable screws 12. These screws are each provided with an enlarged integral collar 13 and with a manipulating head 14 of lesser diameter than the collar. The head 14 and the collar 13 of these screws are separated or spaced apart by a constricted neck 15. All parts of the screw are preferably formed integrally.

The upper cover is provided with a metallic rectangular casing 16 which may be secured to the metal member 6, and which is covered by the members 8 and 9, as shown in Figure 1. The upper binder cover is provided with apertures completely therethrough to permit the passage of the head 14 through such apertures. Preferably the upper binder is provided with a reinforcing eyelet 17 which may be formed of metal, if desired.

The rectangular guide 16 is provided with slots 18, opening from its inner edge at regular intervals. It is to be noted that the rectangular member 16, or guide, is provided with a locking slide 19, having openings 20 through its forward edge to be aligned with the slots 18 when required and is also provided with a slot 21 which extends longitudinally of the slide. While this construction is not essen-

tial to this type of binder, it is so constructed that it can be used with other types as well as this one, thus reducing the cost of construction.

5 It is desirable, in these binders, to provide them with a compression plate 26 equipped with tubular, downwardly extending members 27 adapted to slide over the screws and posts, as shown in Figure 1.

10 In using the device, a stack of sheets, indicated generally at 28, is positioned upon the posts and the plate 26 slipped into place over the posts. Thereafter the cover is positioned and the slide is locked to the screws by sliding it laterally of the cover so that the constricted neck portions of the screws, as indicated at 15, are received in the constricted slots 21 of the slide (see Figure 2). Thereafter the screws are tightened by any suitable means, 15 for example a coin, until the requisite pressure is exerted upon the sheets. It is to be noted in this connection that the screws are freely accessible from the outside of the binder after the binder is locked.

20 The sheets are thus held not merely by the posts, but also by definite and positive frictional grip exerted at their attached end, thus avoiding any possible chance of the sheets tearing away from the posts when they are subjected inadvertently to unusual strains. 25 Also, it is to be noted that the speed of the quickly detachable binders is preserved by this construction and the advantages of the screw-type of binder are at the same time secured.

25 Ordinarily the device is so adjusted by means of the screws that frictional pressure is exerted upon the sheets and also upon the slide. The slide cannot be inadvertently detached, but may be detached under these conditions by merely pressing downwardly with one hand upon the top of the binder. However, if it is desired to insure the locking of the slide against any motion whatsoever, the 40 screws may be tightened to a greater extent to thereby firmly lock the slide against motion.

45 Further, it is to be noted that the device is extremely simple and rugged and is easily produced.

50 Although the invention has been described in considerable detail, such description is intended as illustrative rather than limiting as the invention may be variously embodied and 55 as the scope of such invention is to be determined as claimed.

I claim:—

55 1. A loose leaf binder comprising an upper and a lower cover, means carried by the 60 lower cover for adjustably joining said covers, said means including screws, means carried by the upper cover for quickly locking such upper cover to said screws, said upper cover being apertured to expose the heads of 65 said screws, said screws having collars spaced

downwardly from the heads for preventing the upper cover from sliding downwardly upon said screws beyond a predetermined distance.

2. A loose leaf binder comprising an upper 70 and a lower cover adapted to receive sheets between them, a plurality of posts carried by said lower cover, adjustable screws threaded into the upper ends of said posts, said screws having heads and enlarged collars spaced 75 downwardly from said heads, a guide carried by said upper cover and having openings through which the heads of the screws may project, said openings being of a size to prevent the passages therethrough of said collars, and a locking slide carried by said guide for engaging and locking the screws between the heads and collars, said upper cover having 80 apertures arranged to expose the heads of said screws.

85 In testimony that I claim the foregoing I have hereunto set my hand at Milwaukee, in the county of Milwaukee and State of Wisconsin.
